UNITED STATES PATENT OFFICE

MAX SUHR, OF WEST PALM BEACH, FLORIDA.

DECORATING ROLL.

Application filed December 21, 1922. Serial No. 608,210.

To all whom it may concern:

Be it known that I, MAX SUHR, a citizen of the United States, residing at West Palm Beach, in the county of Palm Beach and State of Florida, have invented certain new and useful Improvements in Decorating Rolls, of which the following is a specification.

This invention relates to certain new and useful improvements in implements designed for use by decorators and the like in decorating walls, and it has for its objects among others to provide a simple yet efficient hand tool that can be used by any house-painter or anyone else and by the use of which the walls of a room can be decorated as quickly in a multiplicity of colors as by hand with a sponge in one color, no previous knowledge being necessary so that the work can be done by unskilled laborers.

It has for a further object to provide a device of this nature that shall be durable and capable of accomplishing a great amount of work without having to replenish any of the parts, and in which any part can be readily replaced when it becomes necessary.

Other objects and advantages of the invention will hereinafter appear, and the novel features thereof will be specifically defined by the appended claims.

The invention is clearly illustrated in the accompanying drawings, which, with the numerals of reference marked thereon form a part of this specification, and in which

Figure 1 is a perspective view of my improved device.

Figure 2 is a detail of the foundation roll or member.

Figure 3 shows the said member or roll with its covering of sponge loosely bound with a string or the like.

Figure 4 is a view of one of the strips of chamois before being applied.

Figure 5 is an enlarged detail showing one of the strips of chamois being secured to the sponge foundation.

Figure 6 is a perspective, on an enlarged scale, of a portion of one of the chamois strips doubled and showing a piece of cord passed through one of the slits thereof.

Like numerals of reference indicate like parts throughout the different views.

In constructing my improved implement I take a pin or roller 1 of wood or other suitable material, of suitable length, say about

six inches, and of suitable diameter, satisfactory results having been obtained with a roller of about five-eighths of an inch in diameter, although these dimensions may be varied at will in accordance with the character of the work to be done, and provide the ends of the roller with suitable means as the pins or the like 2 to form pintles, the latter being mounted in suitable bearings in the spring arms 3, of substantially the shape shown in Figure 1, the other ends of the arms being secured to opposite sides of the block 4 of wood or other suitable material as seen at 5, by screws or otherwise. This member 4 constitutes the handle by which the device may be manipulated, as will be readily understood, it being noted that the device is a hand tool.

Around this roller 1 I wrap a covering 6 of sponge which I confine loosely thereupon by means of a thin strong cord or the like 7, wrapped spirally therearound as seen in Figure 3.

Next I take strips of chamois or analogous material and secure them upon the sponge. I take a strip 8 of this material of substantially the same length as the roller 1 and slit it transversely as seen at 9 at intervals throughout its length, as seen in Figure 4, the slits extending from opposite sides as shown. I then apply these strips to the sponge base. While the sponge might be applied without being tied and held in place by the means that secure the strips in place it is desirable to secure the said sponge in some way to prevent its displacement endwise or otherwise on the roll 1. In applying the strips 8 to the sponge the said strips are doubled upon themselves as seen in Figure 6, and the strips placed lengthwise of the roll and held in place by suitable means as

strings which are removed after the device is complete, and when the strips are all in place they are wound upon the sponge base by strings or the like 10 which are passed through the slits 9 of the strips as seen in Figures 5 and 6 and the strings fastened in any desired manner. All of the ends of the strips between the slits stick out from the roll and are free for movement as will be readily understood upon reference to Figures 1 and 5.

In use, the walls are tinted with any kalsomine, hot or cold, and allowed to dry. Then mix the next color to be used in a pail 110

or other receptacle, making it thinner than for painting. Dip the roll in the color and squeeze with the left hand gently, just enough so that the paint does not run out; then roll the roll down the wall once and then once horizontally. It will mottle about one square yard with one dipping, if there is not too much suction to the wall.

Old walls, if not too dirty, can be rolled 10 right over the old surface, which makes a quick and inexpensive job.

By the use of my roll startling results may be obtained; walls that are beautiful and sanitary can be made with a small expenditure of time and labor.

Modifications in detail may be resorted to without departing from the spirit of the invention or sacrificing any of its advantages.

What is claimed as new is:—

- 20 1. A device of the character described embodying a foundation of absorbent material, and a covering of semi-absorbent material thereon with the latter unconfined at the periphery of the device.
- 25 2. In a device of the character described, a foundation of absorbent material mounted on a revoluble member, and a covering of semi-absorbent material with the latter unconfined at the periphery of the device.
- 30 3. In a device of the character described, a roller comprising a foundation of absorbent material, a revoluble support therefor, and a covering of semi-absorbent ma-

terial having free ends extended in the direction of the periphery of the roll.

35

4. A device of the character described, embodying a revoluble member, a covering of sponge thereon, and a covering of chamois on the sponge disposed axially about said member and having free ends at the periphery thereof.

40

5. A device of the character described comprising a revoluble member, a support therefor with a handle, and a covering of semi-absorbent material slitted and secured 45 thereto and having unconfined ends.

45

6. A device of the character described, consisting of a handle member with arms, a revoluble member journaled in said arms, a sponge covering to said revoluble member, and a covering of strips of semi-absorbent material secured to the same and having 50 free end portions.

50

7. A device of the character described comprising a handle member, arms secured thereto, a revoluble member journaled in said arms, a sponge covering on the revoluble member, and a semi-absorbent covering 55 on the sponge, the said semi-absorbent covering being composed of strips folded 60 upon themselves lengthwise of the revoluble member and having edge slits, and means engaged in said slits and securing the strips in place.

55

In testimony whereof I affix my signature.
MAX SUHR.
